HEATING BOILER

Elmer A. Hooper, Bridgeport, Conn., assignor to
The McCathron Boiler Works Co. Inc., Bridge-
port, Conn., a corporation of Connecticut

Application April 15, 1932. Serial No. 605,449

8 Claims. (Cl. 122—136)

My invention relates to new and useful improvements in oil burning heaters or boilers and refers especially to that class of heater adapted to be made from sheet metal, that is welded, stayed and bolted together to form the required combustion chambers, and relatively long heat passages in addition to the water compartments or jackets, steam dome, etc.

The object of the invention is to design a durable sheet metal type of oil burning furnace adapted for steam, hot water or vapor heating and wherein the combustion and heat passages extend from front to back in a way to cause the heat to traverse the length of the boiler four times at least, better to extract the heat from the hot gaseous products of combustion, the result of which means less loss of fuel and waste of heat up the chimney.

The furnace is adapted to use different makes of oil burners, which is positioned in the lower end door of the furnace to direct the flame and heat into the main combustion chamber. The furnace has no boiler tubes such as most hot water and steam boilers are provided with, since I find that in this type of heater, comprising what is commonly called a flash boiler, wherein oil fuel is used and its consumption controlled by a thermostat, such tubes are of short life as they pull loose and are difficult to repair.

In the construction of my furnace however, I provide in addition to the main outer water jacket of the furnace, a relatively larger removable cylindrical water jacket that extends centrally through the length of the furnace, immediately above the main combustion chamber that serves as a large flue and water container through which the heat and water circulate.

This invention further includes removable closure plates whereby the cylindrical water jacket may be enclosed within the furnace after being positioned therein.

With these and other objects in view, the invention resides and consists in the construction and novel combination and arrangement of parts hereinafter more fully described, illustrated in the accompanying drawings, and pointed out in the claims hereto appended, it being understood that various changes in the form, proportion, size, and minor details of construction within the scope of the claims may be resorted to without departure from the spirit, or sacrificing any of the advantages of the invention.

Similar characters of reference denote like or corresponding parts throughout the several figures of the accompanying drawings forming a part of this specification, and upon which

Fig. 1 shows a front elevation of my improved furnace designed to be made up from sheet metal, the parts of which are welded, stayed and bolted together;

Fig. 2 shows a side elevation as seen from the left side of Fig. 1, smoke pipe and water circulation pipes being omitted;

Fig. 3 shows a central vertical longitudinal section taken on line 3—3 of Fig. 1;

Fig. 4 shows a detail sectional view through the front closure plate and connected parts, taken on line 4—4 of Fig. 1; and

Fig. 5 shows a front view, on a reduced scale, illustrating a modified form of my invention, including two cylindrical water jackets instead of one as in the other views.

The furnace is compactly constructed and is especially adapted for economic burning of oil, as for instance for residential installations, and is of a size and proportion which lends itself to convenient handling. The main body of the furnace includes a lower portion forming a combustion chamber that may be lined with fire brick and upon which the boiler proper is mounted. The cylindrical water jacket hereinbefore referred to comprises a separable unit formed of an inner and outer cylindrical sheet metal wall, producing an annular water jacket that extends through the length of the boiler and is provided with suitable inlet and outlet heat passages so that the same will circulate through the cylinder. The water compartment of this cylinder is provided at its opposite ends with pipe connections with the outer water jacket so that a proper circulation of water through the furnace is assured.

Referring in detail to the characters of reference marked upon the drawings, 10 represents the front end of the furnace having therein a door 11 in which an oil burner 12, see Fig. 3, may be positioned for heating the furnace. 13 represents the rear end of the furnace and 14 a steam dome formed on the top, better to adapt the furnace for steam or vapor heating. When used for steam a safety valve 15 would be employed as shown in Fig. 2. In this view as well as in Fig. 3, is also shown nipples 16—16 for the attachment of service feed pipes, not shown, and an opening 17 for the return water. 18 represents an outlet sleeve for the connection of a smoke pipe of suitable proportion, not shown.

The outer side plates 19—19 as well as the two end plates 20—20 of the combustion chamber may each be formed in part of a single thickness of sheet metal that forms the outer plate of the boiler and against the inner side of which suitable fire brick 21 are positioned so that the lower part of the main combustion chamber 22 is lined on all four sides up to the under edge or leg portions of the main water compartment of the boiler. The outer plate 19 of the boiler heretofore referred to extends up and over to form the sides and top and together with a somewhat similarly formed inner plate 23 and a bottom plate 24 are secured in spaced relation.

thereto by welding and rivets 25, to form an outer water compartment.

The end plates 20-20 form the outer shell of the ends of the boiler and together with inner plates 27, which are secured in spaced relation to the outer plate, form end water pockets 28 that open into the compartment 26 forming a single outer water container. It will thus be observed that the outer or main section of the boiler is hollow with double walls throughout, the 10 interior space therebetween constituting the main water-container portion or pocket of the boiler. In practice this may be covered, as is customary, with any suitable asbestos or other form of insulating material, now shown. A cylindrical opening 29 is formed in both the front and rear ends of the boiler and is provided with gaskets and closure plates 30-30 that are removably secured thereto by screw bolts 31. These openings 29 20 serve to permit of the insertion and removal of the cylindrical water jacket 32 which is supported in the openings 29 of the ends of the boiler and thus forms a central relatively large longitudinally disposed flue 33 through which the 25 products of combustion flow.

Four baffle plates 34-34 and 35-35 are secured to the inner plate 23 of the outer water jacket, the two lower plates 34 being disposed horizontally and extending from one end of the furnace 30 to the other, in close proximity to the outer wall 36 of the cylindrical water jacket 32, separating the combustion chamber 22 from the two upper chambers 37-37 and into which the products of combustion enter through the before mentioned cylindrical water jacket 32. The two upper baffle plates 35-35 which are also attached to the inner plate 23, extend from the rear end of the furnace forward in spaced relation to the front end, forming passages 38 through which the heat 35 and smoke travels rearward, as indicated by arrows "a" in Fig. 3, to the smoke outlet 18.

14 represents the steam dome which is built on the cylindrical top portion of the boiler and communicates with the water chamber 26 through 45 openings 39 in outer boiler plate 19. A suitable gauge 40 may be mounted upon this dome and connected therewith by pipes, as is the water column 41, the try-cocks 42 and the gauge glass 43.

50. 41 indicates the water column which extends down and is connected with the lower portion of the boiler as at 44, to insure a proper circulation and registration of the water within the boiler.

55. The cylindrical water jacket 32 heretofore mentioned is formed of an inner cylindrical plate 45, and outer plate 36, and end plates 46, there being a relatively large central flue 33 therethrough.

60. The products of combustion enter this central flue through the two inlet ducts or passages 48, see arrows "b", Fig. 3, in the forward end portion of the cylindrical water jacket and pass out through somewhat similar outlet passages 49 in 65 the upper portion of the opposite end of the cylindrical water jacket, thereby causing the combustion products to pass from one end of the cylindrical water jacket to the other where they enter the before mentioned chambers 37-37 in 70 the two sides of the furnace and wherein the said products of combustion travel forward along the baffle plates 34 and through the openings 38 whereby they are free to enter the forward end 75 of the top passage 50 formed between the cylinder and the under plate of the boiler, where

they are free to again travel rearward and out of the smoke outlet 18, see arrow "a".

The annular chamber of the cylindrical water jacket is connected with the main boiler by suitable circulating pipe connections 51 and 52, the former being connected between the lower forward end portion of the cylinder and the front of the boiler, whereas the latter is connected with the rear upper portion of the cylinder and the top portion of the boiler, thereby insuring a circulation of water through the cylinder. 85

From the foregoing, it will be understood that the products of the combustion pass from the brick lined fire chamber 22 through the two inlet passages 48 to the chamber in the cylinder and through which they pass and then go out through upper outlet passages 49 in the opposite side of the rear end portion of the cylinder when they pass into the rear end of the two longitudinal chambers 37 formed between the baffle plates 34 and 35. The products of combustion thereupon travel forward in these passages and through the passage 38 at the end of baffle plate 35 where the products again travel back through the single uppermost passage 50 to the rear and 100 out into the stack. This construction causes the products of combustion to travel the length of the furnace four to five times and at all times between water-filled parts of the boiler that serves to thoroughly absorb the heat so that by 105 the time the remaining products, the smoke, reach the stack they are cooled. It will also be noted that all water containing chambers of the boiler are comparatively thin and are exposed to the fire on one or both sides so as to insure 110 quick and thorough heating.

The size and number of the circulating pipes 51 and 52 may be increased, or their particular location on the boiler may be changed, if desired, as can also the location of the burner 115 nozzle herein shown, at what I have described as the front end of the furnace, though it may equally as well be located in the opposite end.

It will further be seen that should it be necessary to clean out the boiler or to repair the 120 cylindrical water jacket, it can be readily done by first removing the circulating pipes and then the screw bolts 31 in the end plate or plates 30, which can be taken off in a way to open the ends of the boiler and permit the withdrawal of the 125 water jacket. This being removed, the other flues and passages of the furnace may be readily gotten at.

In Fig. 5 I have shown a modification of my invention to include two cylindrical water jackets 130 32 having flues, passages, and circulating pipe connections like those heretofore described, but contained within a single outer water jacket, and beneath a single dome. In this construction, the main combustion chamber 21 is proportionately 135 wider than that shown in the other figures and may be provided with one or more oil burners. In this form, I use an additional baffle plate 34^a that is positioned between the two cylindrical water jackets 32 and, like the two outer baffle plates 140 34, serves to direct the products of combustion through the inlet so as to insure a proper circulation from front to rear through the water jacket and into the upper chambers, as in the other form of construction. 145

Having thus described my invention, what I claim and desire to secure by Letters Patent is:

1. A boiler of the class described comprising a main outer water jacket having a combustion chamber in its lower portion and a smoke outlet 150

- at the top, a cylindrical water jacket removably positioned in the two ends of the outer water jacket and extending the length of the boiler and having a central heat passage therein, inlet heat 5 passages through the sides of one end portion leading into the central passage, outlet heat passages through both sides of the other end portion leading from the central passage, a circulating pipe connecting the main outer water jacket with 10 the end of the inner cylindrical water jacket, elongated baffle plates between the sides of the cylindrical water jacket and the enclosing outer jacket, forming separate elongated passages between the outer and inner water jackets through 15 which the heat and smoke pass to the outlet.
2. A boiler of the class described comprising a main outer water jacket having a combustion chamber in its lower portion and a smoke outlet at the top, a cylindrical water jacket removably 20 positioned in the opposite end portions of said outer water jacket and having a central longitudinal heat passage therein and inlet heat passages through one end portion communicating with the first mentioned passage, an outlet heat passage 25 through the other end portion, a circulating pipe connecting the outer water jacket with the inner cylindrical water jacket, removable plates for closing the ends of the cylindrical water jacket, elongated baffle plates between the sides of the 30 cylindrical water jacket and the enclosing outer jacket, forming a separate elongated passage on each side between the outer and inner water jackets through which the heat and smoke pass to the smoke outlet.
- 35 3. A boiler of the class described comprising an enclosing water jacket having a combustion chamber in its lower portion and aligned openings in its opposite ends and a smoke outlet at the top, an elongated removable water jacket positioned in the boiler and resting in the said openings, said removable water jacket including a flue and inlet passages thereto through one side portion, and outlet passages therefrom through another side portion, removable plates for closing 45 the ends of flue, elongated baffle plates between the sides of the removable water jacket and the enclosing water jacket, forming three separated elongated passages between the outer and inner water jackets through which the heat and smoke 50 pass to the outlet.
4. A boiler of the class described comprising an enclosing water jacket having a combustion chamber in its lower portion and aligned openings in its opposite ends, an inner cylindrical water container having a longitudinal fire flue extending therethrough positioned in the boiler with its end portions resting in the said openings, and with its outer plate member in spaced relation to the inner wall of the enclosing water jacket, flue inlet and outlet in said longitudinal fire flue, 55 closure plates removably attached to the ends of the boiler, closing its aligned cylindrical openings and the ends of the flue extending through the water jacket, circulating pipes connecting the outer enclosing water jacket and the inner cylindrical water jacket.
- 60 5. A boiler of the class described comprising an enclosing water jacket having a combustion chamber in its lower portion and aligned cylindrical openings in its opposite ends and a smoke outlet at the top, a removable cylindrical water jacket positioned in the boiler and loosely supported in the cylindrical openings, with its outer
- cylindrical member in spaced relation to the inner wall of the enclosing water jacket, said removable water jacket including a central flue extending the length thereof, a flue inlet through the lower side portion, an outlet flue through the upper side portion of said removable jacket, removable plates for closing the ends of the openings, circulating pipes positioned exterior of the boiler connecting the outer enclosing water jacket and the inner removable water jacket, elongated baffle plates between the sides of the cylindrical water jacket and the enclosing water jacket, forming separated elongated passages between the outer and inner water jackets through which the heat and smoke pass to the outlet.
- 65 6. A boiler of the class described comprising an enclosing water jacket having a combustion chamber in its lower portion and aligned openings in its opposite ends and a smoke outlet at the top, an elongated water jacket removably positioned in the boiler above the combustion chamber with its ends supported in the aligned openings, and in spaced relation to the outer water jacket, said cylindrical water jacket including a central longitudinal opening forming a heat 70 passage therethrough and a heat inlet and outlet through the sides of the cylindrical water jacket, heat passages formed between the sides and top of the cylindrical water jacket and the outer water jacket through which the heat and smoke pass to the outlet, and circulating water pipes positioned exterior of the boiler connecting the outer water jacket with the inner cylindrical water jacket.
- 75 7. A boiler of the class described comprising an enclosing water jacket having a combustion chamber in its lower portion and aligned cylindrical openings in its opposite ends and a smoke outlet at the top, a cylindrical water jacket having a central longitudinal opening therethrough positioned in the boiler and freely resting in the cylindrical openings, with its outer cylindrical member in spaced relation to the inner wall of the enclosing water jacket, and a heat inlet and outlet through the sides of the cylindrical water jacket plates for closing the ends of the aligned openings in the boiler and cylindrical water jacket, elongated baffle plates between the sides of the cylindrical water jacket and the enclosing water jacket, forming a series of separated elongated 80 passages between the outer and inner water jackets through which the heat and smoke pass to the outlet.
8. A boiler of the class described comprising an enclosing water jacket having a combustion chamber in its lower portion and aligned cylindrical openings in its opposite ends and a smoke outlet at the top, a cylindrical water jacket extending through the main body of the boiler above the combustion chamber and into the cylindrical openings, said cylindrical water jacket having a central longitudinal opening therethrough, inlet passages through the sides of one end portion, and outlet passages through the sides of the opposite end portion of said cylindrical water jacket, elongated baffle plates between the sides of the cylindrical water jacket and the main water jacket, forming elongated heat and smoke passages between the outer and inner water jackets through which the heat and smoke 85 pass to the outlet, and a steam dome on top of the boiler and communicating therewith.

ELMER A. HOOPER.
